his ATTORNEY

UNITED STATES PATENT OFFICE.

EDMUND H. SANDKUHL, OF BROOKLYN, NEW YORK, ASSIGNOR TO DAVID H. ZELL, INC.,
OF NEW YORK, N. Y., A CORPORATION OF NEW YORK.

COIN BANK.

Application filed April 4, 1927. Serial No. 180,663.

This invention relates to coin banks, and has for its primary object to provide a bank having one or more coin receiving raceways with a single combined ingress and egress slot or opening for each raceway, together with novel and simply constructed key-actuated means which will permit of the insertion of the coins through said slot or opening but normally effectively bar or prevent the removal of the coins therethrough.

In a practical embodiment of my present improvements, the bank structure consists essentially of a central metal plate and sheet metal side walls which may be either integral or separate from each other arranged in spaced parallel relation to the opposite sides of said central plate permanently fastened or secured to the marginal edges thereof. These sheet metal side walls are embossed to form the coin receiving channels or raceways in conjunction with the intermediate metal plate, said raceways at one of their ends being closed by one side margin of the bank structure and opening at their other ends through the opposite side margin thereof. Adjacent to said openings a recess is provided in the edge of the central plate in which a key-actuated shiftable member is arranged and carries spring fingers projecting over said openings at one of their ends and yielding inwardly under the pressure of the coins but preventing outward movement of the coins from the raceways. It is one of the important features of the invention to provide effective means for locking or retaining this shiftable member against movement relative to said plate by an implement inserted through the opening of the raceway, or by any other means than the proper key.

It is a further general object of my invention to provide a locking means for the coin raceways of banks of the above character which is exceedingly simple in its construction, effective and reliable in practical use and may be manufactured at comparatively small cost.

With the above and other objects in view, the invention consists in the improved coin bank and in the form, construction and relative arrangement of the several parts thereof as will be hereinafter more fully described, illustrated in the accompanying drawing and subsequently incorporated in the subjoined claims.

In the drawing, wherein I have illustrated

one simple and practical embodiment of the invention, and in which similar reference characters designate corresponding parts throughout the several views,

Figure 1 is a side elevation illustrating a preferred embodiment of the device;

Fig. 2 is an edge view thereof partly in section;

Fig. 3 is an elevation of the bank showing the reverse side thereof from that seen in Fig. 1;

Fig. 4 is a fragmentary elevation partly in section showing the key-actuated locking means in normal position;

Fig. 5 is a similar view showing the position of the key-actuated locking means after it has been operated to permit of the removal of the coins;

Fig. 6 is a detail perspective view of the locking device, and

Fig. 7 is a similar view of the key.

Referring in detail to the drawing, it will be noted that the bank structure as a whole is quite flat or thin so that it may be conveniently carried in the pocket, said structure including a central metal plate 5 and the parallel side walls of sheet metal 6 at opposite sides thereof. These side walls each have portions indicated at 7 in bearing contact against the plate 5 and embossed portions 8 which are spaced from the side face of said plate, thereby producing in conjunction with the plate, coin receiving raceways 9. These embossed portions of the side plates 6 are provided with spaced openings 10 therein coinciding with similar openings 11 in the plate 5, so that the coins contained in said raceways will be visible. I have herein shown the embossed parts of the plates 6 in the form or configuration of the conventional dollar sign, but it will, of course, be understood that in so far as my present improvements are concerned, this is not essential, and said embossed portions of the plates and consequently the coin receiving raceways may be of various other forms.

The marginal edge of one of the plates 6 is angularly bent and engaged over the edges of the intermediate plate 5 as shown at 12 and the extreme edge thereof, together with the edge of the other plate 6 is folded inwardly and said edges clinched together as at 13 to thereby fixedly secure the side plates 6 in assembled relation with the intermediate plate 5.

The coin receiving raceways 9 in the illus-

trated construction terminate upon one of the side marginal edges of the bank structure adjacent one end thereof and are closed while the other ends of said coin raceways terminate 5 on the opposite side marginal edge of the bank structure adjacent its other end and open through the marginal portion 12 of one of the side plates 6, said marginal portion of the side plate being provided with the spaced 10 longitudinally extending slots 14 therein for this purpose. Through these slots, the coins are adapted to be inserted into and removed from the respective raceways.

Banks of this character are commonly distributed by large banking institutions for the purpose of increasing deposits, the depositor to whom the bank is loaned inserting the proper coins into the raceways until they are filled to capacity, when the coin bank is 15 turned into the banking institution and the proper official, by means of a suitable key, opens the bank and removes the coins, crediting the amount thereof upon the depositor's account. I have devised a very simple and 20 effective means for preventing the removal or extraction of the coins from the raceways by the depositor after they have once been inserted therein. To this end, the central plate 5 of the bank structure at one of its 25 edges and adjacent to the slots 14 is provided with a longitudinally extending recess 15 therein having an angular extension thereof at its inner side as shown at 16 which coincides with a keyhole slot 17 provided in one 30 of the side walls 6 of the bank. In spaced relation to this extension 16, the inner edge of the recess is further provided with a shoulder 18, the purpose of which will be presently pointed out.

40 A key-actuated member 19 is longitudinally movable in the recess 15 and as herein shown, this member is in the form of a short metal bar having a laterally offset end portion 20 provided with a convex or curved edge 21 opposed to the marginal wall 12 of the bank structure. The opposite edge of this offset end 20 of the member 19 is of 45 stepped formation to provide a terminal tooth or lug 22 adapted to cooperate with the shoulder 18 and a recess 23 in spaced relation to said tooth. To the outer edge of the member 19 at its other end, one end of a leaf spring 24 is fixed, said spring being bowed or curved as seen in Fig. 4 of the drawings, and 50 extending at its other end slightly beyond the end 20 of the member 19 and in spaced relation to the curved edge 21 thereof.

The key 25 shown in detail in Fig. 7 of the 55 drawings, consists merely of a flat metal shank having a slot or recess 26 opening upon one side edge thereof adjacent one of its ends to provide a finger 27.

Normally, the locking member 19 and spring 24 are in the position shown in Fig. 4 of the drawings, in which it will be ob-

served that the spring 24 bearing against the marginal wall 12 of the bank acts to press the member 19 inwardly to hold the tooth 22 thereof in engagement upon the shoulder 18 and in contact with the inner edge of recess 15 at the lower side of the extension 16 thereof. The free portion of the spring 24 is longitudinally split as shown in Fig. 6 of the drawings at 28 to provide independently yieldable portions which project upwardly 75 above the lower ends of the respective slots 14. Thus, in this normal position of the parts, as shown in dotted lines in Fig. 4, when the coin is inserted through either of the slots 14, one part of the spring 24 is 80 pressed inwardly and downwardly upon the curved end edge 21 of the member 19, said coin rolling over this spring finger and into the coin raceway where it continues its rolling movement until it comes to a position of rest in the other end of said raceway or in contact with another coin previously inserted therein. When the coin passes beyond the spring finger, said finger immediately returns to its normal position where it projects above 85 and closes the lower end of the slot 14 against any possibility of the coin in the raceway moving outwardly through said slot. Thus, it will be apparent that after the coin is once 90 inserted, it is impossible to extract or remove 95 the same from the bank.

When the bank has been filled with coins and it is turned over to the proper bank official having the key 25, the end of the key is 100 inserted through the keyhole 17 in one of the side plates 6 until it abuts against the opposite side plate 6, at which time the finger 27 on the end of said key will be engaged at its extremity in the notch or recess 23 in the locking member 19. The key is now turned 105 in anti-clockwise direction whereby a rocking motion is imparted to the member 19 from a fulcrum point at the lower side of the recess extension 16 against the action of the spring 24 and tooth 22 is thereby disengaged from 110 the shoulder 18 so that in the continued turning movement of the key, the member 19 together with the spring 24 is shifted longitudinally in the recess 15 to the position shown in Fig. 5 of the drawings, wherein the 115 free end of the spring 24 is disposed out of alignment with the end of the slots 14 so that the coins may freely move outwardly there-through. Thus the contents of the bank can 120 be easily and quickly removed, after which the movement of the key is reversed to return the locking means to its former position 125 shown in Fig. 4 of the drawings.

From the foregoing description, considered 130 in connection with the accompanying drawing, the construction and manner of operation of my improved coin bank will be clearly and fully understood. It will be seen that I have provided very simple and effective means for retaining the coins in the raceways

and preventing their extraction which enables me to both insert and remove the coins from the same ends of the raceways. At the same time, the above described means for effecting this purpose, is of exceedingly simple character, not liable to get out of order and may be utilized in connection with such coin banks without materially increasing the manufacturing cost thereof.

10 While I have herein shown and described an embodiment of my present improvements which has given excellent service in practical use, it will nevertheless be understood that the device in its several essentials is susceptible of embodiment in various other alternative structures, and I accordingly reserve the privilege of resorting to all such legitimate changes therein as may be fairly embodied within the spirit and scope of the invention as 20 claimed.

I claim:

1. A coin bank consisting of a bank structure having a coin receiving raceway opening at one of its ends through the marginal edge of 25 said structure and closed at its opposite end, a shiftable, inwardly yieldable, element permanently housed in said structure and adapted to prevent the outward movement of a coin through the open end of the raceway but permitting of its inward movement therethrough into the raceway, and key-actuated means for shifting said element to and from such position in the path of movement of the coin.

35 2. A coin bank consisting of a bank structure having a coin receiving raceway opening at one of its ends through the marginal edge of said structure and closed at its opposite end, a shiftable inwardly yieldable element 40 permanently housed in said structure and adapted to prevent the outward movement of a coin through the open end of the raceway but permitting of its inward movement therethrough into the raceway, a part 45 connected with said shiftable element and provided with means adapted for engagement by a key to actuate said part and shift said element to and from a position in the path of movement of the coins, and means 50 locking said part in a normal position against

movement to retain said element in position to prevent the extraction of the coins.

3. A coin bank consisting of a bank structure having a coin receiving raceway opening at one of its ends through the marginal edge of said structure and closed at its opposite end, a shiftable, inwardly yieldable, element permanently housed in said structure and adapted to prevent the outward movement of a coin through the open end of the raceway but permitting of its inward movement therethrough into the raceway, a part 55 connected with said shiftable element and provided with means adapted for engagement by a key to actuate said part and shift said element to and from a position in the path of movement of the coins, said part having a locking tooth, and a part of the bank structure having a shoulder, said tooth being urged by said yieldable element into engagement with said shoulder to normally lock said part against movement and retain the yieldable element in position to prevent the extraction of the coins. 60

4. A coin bank having a central plate and side plates formed to provide coin receiving raceways closed at one of their ends and opening at their other ends through the marginal edge of the bank structure, said central plate adjacent the open ends of the raceways having 75 a recess and a shoulder at one side of said recess, a shiftable part permanently housed in said structure in said recess having a tooth at one end to engage said shoulder, an element 80 carried by said shiftable part and movable therewith into or out of said raceways, said element being constructed to permit of the insertion of the coins into said raceways when in one position but to prevent their extraction therefrom, and one of the side plates of 85 the bank structure having an opening to receive a key and said shiftable part having means engageable by a part of the key whereby said shiftable part may be disengaged from said shoulder and actuated to move 90 said element into or out of the path of movement of the coins. 95

In testimony that I claim the foregoing as my invention, I have signed my name hereto.

EDMUND H. SANDKUHL.
